UNITED STATES PATENT OFFICE.

ROBERT A. WILSON, OF DALLAS, TEXAS, ASSIGNOR TO THE GUIBERSON CORPORATION, OF DALLAS, TEXAS, A CORPORATION OF DELAWARE.

POWER WRENCH.

Application filed January 2, 1926. Serial No. 78,806.

This invention relates to new and useful improvements in power wrenches.

In certain types of couplings, such as tool and pipe joints and tubing, which are frequently used in a string of pipe or tubing extending from two to three thousand feet into a well, the parts become so tightly screwed together that it is impossible to unscrew the coupling with a manually operated wrench. Such couplings are usually formed with shoulders and these bind, causing the flat surfaces to frictionally adhere.

The object of my invention is to provide a wrench having complementary members for engaging the individual members of a joint coupling, together with means for swinging the wrench members in opposite directions, whereby the joint is broken or rotated sufficiently either to free the coupling members or to screw them together.

A further object is to provide means for increasing the power applied by swinging a lever, to a point of exerting sufficient force to operate the joint breaking members.

Another object is to provide oppositely movable operating members for swinging the joint engaging members, together with means for moving said operating members in opposite directions.

A still further object is to provide means for compounding the leverage, whereby ample power is applied to break the obstinate joint.

A particular object of the invention is to provide a wrench which may be operated with considerable speed as well as developing sufficient power to perform its work.

Another object of the invention is to provide the support of the wrench with means whereby it may be movably suspended so as to be more easily handled and also more readily applied to the work, as well as compensating the swing of the joint-engaging members, when the latter are pivoted to the actuating bars.

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is an elevation of a wrench constructed in accordance with my invention, 55 and in position on a joint;

Fig. 2 is a plan view of the same.

Fig. 3 is an elevation of the wrench carriage, a portion being in section;

Fig. 4 is an enlarged sectional view taken 60 on the line 4—4 of Fig. 3;

Fig. 5 is a side view of the carriage of a modified form, a portion being in section;

Fig. 6 is an elevation of the same;

Fig. 7 is a transverse sectional view taken 65 on the line 7—7 of Fig. 8, a portion being in section;

Fig. 8 is a side elevation of another form in which the invention may be carried out;

Fig. 9 is a transverse sectional view of still 70 another form, a portion being in section;

Fig. 10 is a transverse sectional view of another form, a portion being in section;

Fig. 11 is a side view of another form of 75 connecting the actuating bars and the joint engaging member;

Fig. 12 is a plan view of a further modification of the forms in which the invention may be carried out;

Fig. 13 is a side view of the same partially in section; and

Fig. 14 is an end view of the same.

This application is a continuation in part of my former application filed October 9, 1924, Serial No. 742,562. 85

In the drawings the numeral 10 designates a wrench carriage which may be of any suitable construction, and is shown in Figs. 1 to 4 as composed of complementary members bolted together. The carriage has upper and lower channels or guideways 11 separated by a transverse web 12. Rack-bars 13 are slidable in the guideways in opposite directions. Each bar has a head 14 on one end provided with an angular socket 15. 90

A shaft 16 is journaled in the carriage at right angles to the bars and has a handle bar 17 fastened on its rear end. The handle bar has rearwardly directed handles 18 on its ends. A pinion 19 is confined in a slot 20 in the web 12 and is fastened upon the shaft. The rack-bars 13 have their teeth in mesh 100 with the pinion. When the handle bar 17 is revolved the pinion is revolved and the bars are moved in opposite direction. The carriage has an eye 21 which may receive a hook 105

of a supporting line (not shown) in the derrick, whereby the carriage 10 is movably suspended.

The heads 14 are located on opposite ends 5 of the bars 13 and receive wrench members 22 which latter have rigid jaws 23. In Figs. 1 and 2 is shown a tubular joint composed of an upper coupling A and a lower coupling B, said coupling having wrench faces C for receiving the jaws 23. The wrench members 22 are formed so that when their jaws are in engagement with the couplings, their shanks will diverge, whereby their rear ends are spread apart.

15 Each member 22 has a tenon 24 at its rear end bent parallel to the shaft 16 and inserted in the socket 15 of the adjacent head 14. The wrench members are removable and others with jaws of a different size may 20 be readily substituted.

In Figs. 5 and 6 a modified form of carriage is shown. The carriage comprises a 25 housing 30 having an offset 31 and is supported by an eye 32. The rack-bars 13 are mounted in the offset as is the pinion 19, but the pinion is mounted on a stub shaft 33 extending into the main housing 30. A spur gear 34 is keyed on the shaft 33 and is driven by a pinion 35 mounted on a counter- 30 shaft 36. A second gear 37 is also fastened on the shaft 36 and is driven by a pinion 38. A shaft 16' corresponding to the shaft 16 on which the handle bar 17 is fastened, is mounted in the housing and has a spindle 39 on its inner end bearing in a socket in 35 the end of the shaft 33.

It will be seen that in the form shown in Figs. 1 to 4, the turning force applied to the handle bar 17 is imparted direct to the pinion 19, and while an advantage is had 40 through the leverage of the handle, it would be laborious to break an extremely tight joint. In the form shown in Figs. 5 and 6 the leverage is multiplied or compounded 45 by reason of the gear 37, pinion 35, and gear 34 and sufficient force will be applied to the pinion 19 to move the bars 13 and readily break any joint.

In operating the wrench the carriage 10 or 50 30 is hung in the derrick by the tackle in the usual manner, the eye 21 or 32 being provided for this purpose. The rack-bars 13 are adjusted to the position shown in Figs. 1 and 2. The wrench members 22 are engaged with faces C of the couplings A and B. By revolving the handle bar 17 rotation is imparted to the pinion 19 and the bars 13 are thus moved rapidly outwardly, whereby the members 22 are spread 55 and the jaws 23 are swung in opposite directions. The tenons 24 are long enough to remain in the sockets 15 during the movement of the bars.

60 However, the carriage being suspended and free to swing, it is not necessary for

the tenons to have sliding connection with the bars 13. The suspension of the carriage also makes it easy to adjust and to handle in positioning the jaws 23 on the joint.

The swinging of the wrench members 22 70 will rotate the couplings A and B in opposite directions, thus disengaging their contacting shoulders. The rotation will be sufficient to free the couplings and further rotation may be completed with the usual wrench. It will be seen that this wrench may be used to tighten a joint by spreading the rack-bars 13 and then operating them to swing the members 22 together. My invention 75 may be advantageously used with the type of joint shown in my Letters Patent No. 1,507,877, issued September 9, 1924.

It will be at once apparent that many 80 different structures may be evolved in carrying out the invention and I have endeavored to illustrate some of these different forms.

In Figs. 7 and 8 I have shown an L-shaped carriage 40 suspended by an eye 41. A pair 85 of miter gears 42 and 43 are journaled in the housing and the gear 42 has a double hub 44 extending through the housing. Transverse bars 45 are secured in the said hub so as to be rotated by the latter. On one side of the hub the bar has right-hand screw-threads 46 and on the other side of 90 said hub the bar is provided with left-hand screw-threads 47. Traveling blocks 48 are mounted on these threaded portions of the bars and when the latter are rotated, said blocks are moved toward each other or spread apart. The tenons 24 of the wrench members 22 are pivoted on studs 49 carried by the blocks.

105 In Fig. 9 the gear 42 is fastened centrally on an elongated sleeve 50 which is journaled in the carriage 40. The sleeve has right-hand screw-threads 51 in one portion of its bore and left-hand screw-threads 52 in the opposite portion of its bore. Correspondingly screw-threaded bars 53 and 54, respectively engage in the threads 51 and 52, and each bar has a socket or loop 55 on its outer end. The tenons 24 of the wrench members 22 are pivoted on bolts 56 in the 110 sockets.

115 Fig. 10 presents another form in which bars 60 extend from the hub 44 of the gear 42. One of the bars has right-hand screw-threads 61, while the other has left-hand screw-threads 62. The bars engage in externally screwed barrels or members 63 having heads on their outer ends to which the tenons 24 of the member 22 are pivoted by 120 bolts 65.

125 In connection with the forms shown in Figs. 7 to 10 inclusive, it will be seen that upon rotating the gears 42 and 43 by the shaft 16, the bars 45 and 60 or the sleeve 130 50 is rotated. This causes the parts con-

nected with the tenons 24 to be moved toward each or spread apart, whereby the wrench members 22 are actuated. In Fig. 11 a clevis type of connection 66 is shown 5 pivoted to the tenon 24.

By suspending the carriage it is possible to make quite a variation in the wrench structure, and such an example is given in Figs. 12, 13 and 14. A cylindrical carriage 10 is suspended by a hook 71 and one of the wrench members 22 is fastened rigidly to the bottom of the carriage. A segmental rack-bar 72 is slidable transversely of the top of the carriage on a guide 73 and has 15 upstanding lugs 74 at its central portion. The upper wrench member 22 has a reduced finger 75 at its end engaging loosely between the lugs.

The rack-bar 72 is driven by a gear 76 and 20 is connected to any suitable planetary differential gearing, such as is indicated in Fig. 13. The gear is driven by the shaft 16 on which a hand wheel 77 is mounted. In operating this form the hand wheel 77 is revolved and motion transmitted to the gear 76, whereby 25 the rack-bar 72 is actuated. This causes the upper wrench member 22 to be swung while the lower member 22 remains stationary and so holds the lower joint B.

The handle 17 or other operating means 30 may be readily spun or rapidly revolved and this makes for quick operation, which is highly desirable, because time is one of the most important elements in the drilling 35 of wells and the handling of sucker rods and the like.

Various changes in the size and shape of 40 the different parts, as well as modifications and alterations, may be made within the scope of the appended claims.

What I claim, is:

1. In a joint breaking wrench, a carriage, 45 a pair of oppositely sliding bars mounted therein and each having wrench connecting means at one end of the carriage, wrench members having jaws and opposite operating ends movably embraced by the connecting means to travel in opposite directions with the bars, and means for oppositely moving said bars to swing the wrench members.

2. In a joint breaking wrench, a carriage, 50 a pair of oppositely movable bars having sockets and mounted in said carriage, a pair of wrench members having jaws and free ends embraced by said sockets for movement therewith in the opposite travel of the bars, and means for sliding the bars in opposite directions to swing the wrench members.

3. In a joint breaking wrench, a carriage, 55 a pair of oppositely movable bars having sockets and mounted in said carriage, a pair of wrench members having jaws and free ends embraced by said sockets for movement therewith in the opposite travel of the bars, a pinion interposed between the bars for

actuating the same, and geared means for revolving said pinion.

4. In a joint breaking wrench, a carriage, 60 a pair of oppositely slidable rack-bars mounted in the carriage, means for actuating the bars, a head on each bar having an enclosing socket, and a pair of wrench members each having a rigid jaw at its outer end and a free inner end embraced by the socket of one of the jaws for movement of the 65 wrench members thereby in opposite directions.

5. In a joint breaking wrench, a carriage 70 comprising complementary members provided with parallel guideways and an intermediate transverse web, oppositely movable rack-bars disposed in the guideways and separated by the web, apertured heads at the outer ends of the rack-bars forming sockets, a pinion pivoted in said members intermediate the rack-bars to actuate the same, a hand-operated member for rotating said pinion, and wrench members having jaws and free ends slidable in the sockets in the 75 opposite movements of the jaws.

6. In a joint breaking wrench, a carriage, 80 oppositely movable actuating members mounted therein, a plurality of swinging wrench members having joint engaging jaws at their outer ends and their opposite ends 85 being positively connected to the actuating members for movement therewith in either direction, and means for moving said actuating members in unison.

7. In a joint breaking wrench, a support, 90 a pair of oppositely movable actuating members mounted therein, a pair of wrenches having jaws and opposite operating ends connected to said members to effect a simultaneous travel of both wrenches, means for 95 jointly operating said members, and means for movably suspending the support.

8. In a joint breaking wrench, a support, 100 a pair of oppositely movable actuating members mounted therein, a pair of wrenches having jaws and opposite operating ends 110 connected to said members to effect a travel of both wrenches toward and from each other and in opposite directions, means for jointly operating said members, and means for movably suspending the support.

9. In a joint breaking wrench, a support, 115 oppositely movable sliding members mounted therein, a pair of wrenches having jaws and opposite operating ends slidingly and 120 pivotally connected to said members to effect a travel of one wrench in one direction and the other wrench in an opposite direction, and means for operating said members in unison.

10. In a joint breaking wrench, a carriage, 125 means for suspending the carriage opposite the joint to be worked upon, upper and lower wrench members having jaws for engaging the upper and lower couplings of the 130

joint, and means for actuating the wrench members to break or fasten the joint.

11. In a joint breaking wrench, a carriage, the carriage being movable toward and from the joint, means for suspending the carriage opposite the joint to be worked upon, upper and lower wrench members having jaws for engaging the upper and lower couplings of the joint, and means for actuating the wrench members to break or fasten the joint.

12. In a joint turning wrench, a carriage, means for supporting the carriage opposite the joint to be worked upon, upper and lower wrench members having jaws for engaging the upper and lower couplings of the joint, oppositely movable members positively connected with said wrench members for swinging said wrench members toward or

away from each other, said wrench members being held against movement longitudinally 20 of the movable members, an operating element connected with said movable members, and means for operating said element.

13. In a joint turning wrench, a carriage, means for movably suspending the carriage 25 opposite the joint to be worked upon, said carriage being free to move toward and from the joint, upper and lower wrench members having jaws for engaging the upper and lower couplings of the joint, oppositely movable members 30 to which the wrench members are positively connected for swinging in either direction, and means actuating the movable members in opposite directions.

In testimony whereof I affix my signature.

ROBERT A. WILSON.
